TURRET INSTALLATION WITH AMMUNITION FEED MECHANISM

Quinton C. Johnson, Torrance, Calif., assignor to North American Aviation, Inc.

Application November 17, 1954, Serial No. 469,497

9 Claims. (Cl. 89—37.5)

The present invention relates generally to aircraft gun turrets and more particularly to improved ammunition feed mechanisms therefor.

In the design and operation of gun turrets for aircraft, the cone of fire defined by the range of movement of the turret is frequently materially restricted by the clearance requirements of the ammunition feed chutes. The present invention is directed to an improved ammunition feed chute guide mechanism for an aircraft gun turret such as may be installed in the tail of an airplane. The range of movement of such turrets is usually restricted by interference between the flexible ammunition feed chutes, which enter the turrets for the twin machine guns, and the wall structure adjacent the opening in the aircraft. The present improvement is directed to means for automatically positioning the flexible ammunition feed chutes to obtain the maximum clearances as the turret is rotated. The improved mechanism thereby eliminates the interferences which have heretofore been encountered and which restricted the range of movement of the turret, and the cone of fire of such turrets has been materially increased.

Numerous efforts have been made to provide flexible guide means for ammunition feed chutes and these prior arrangements have for the most part been of the demand type utilizing the "force" or "pull" methods which have provided doubtful feed characteristics and in many installations resulted in damage to the chutes. Most of these prior devices permitted freedom of the ammunition chute to twist or change its position and direction in accordance with the demands of the movement of the guns or turrets; but in contrast, the present improved mechanism provides for the coordinated guidance of the chute by anticipating and positioning the chute to provide the maximum clearance when the chute is rotated with the turret toward the adjacent supporting structure, and to thereby insure positive feeding without chute damage.

These and other objects and advantages of the present invention will become obvious to those skilled in the art following a reading of the present specification, taken in conjunction with the accompanying drawings, forming a part hereof, in which:

Fig. 1 is an elevational view of the tail portion of an aircraft showing a turret to which the improved ammunition feed guide mechanism has been applied;

Fig. 2 is a transverse sectional view, to a larger scale, of the installation looking rearwardly as taken along the lines 2—2 of Fig. 1;

Fig. 3 is a perspective view of the turret and associated mechanism of Fig. 2 as viewed looking angularly and rearwardly with the turret rotated in azimuth to an extreme position toward the left;

Fig. 4 is an enlarged view of the actuating mechanism for the chute guide means as taken along the lines 4—4 of Fig. 2;

Fig. 5 is a sectional plan view of the guide roller as-

sembly shown in Fig. 2 as taken along the lines 5—5 thereof; and

Fig. 6 is a detailed cross-sectional view showing the feed chute adapter mounting as taken along the lines 5—6 of Fig. 2.

In Fig. 1, there is shown a portion of the tail or empennage of an aircraft 5 having a fuselage portion 5a, a vertical tail portion 5b and horizontal tail surfaces 5c. Within an opening 5d, at the extreme aft portion of the fuselage 5a, for rotation about both its vertical and horizontal axes, is mounted a ball type turret 6 to which are fitted a pair of remotely fired machine guns 7. While the turret 6 is shown by way of example as a remotely controlled ball type, it may be of other than the type shown as the present improvement is also applicable to such other types and to other vehicles than aircraft. The turret 6 may be rotated in azimuth about its vertical axis A—B by means of an electric motor 6b through the drive gearing 6c and the guns may thereby be swept in the horizontal plane (in azimuth or traverse) either to the right or to the left of their normal rearwardly trained positions. The turret 6 may also be rotated in a well known manner about its main horizontal axis C—D, or in elevation, by means of a second electric motor 6d and suitable gearing 6e, which may preferably be housed within the ball turret, in a manner well known in the art. The numeral 8 indicates the flexible ammunition feed chutes for the machine guns 7 entering through the surface of the ball turret through the guide adapter 40, chute 8L guided through adapter 39 and chute 8R through adapter 40. (See Fig. 3.)

Fig. 2 shows the ball turret 6 in its central position looking rearwardly with the right and left hand guns 7R and 7L centered about both the vertical and horizontal axes, or with the guns level and trained directly longitudinally toward the rear of the aircraft. The turret assembly 6 is suitably housed within the fuselage opening 5d and supported from the structural framework thereof which may consist essentially of the cross-tie member 5e attached to the straightened vertical portions of the adjacent fuselage former ring 5f. The ball turret 6 is provided with forwardly facing access openings 6a which provide openings for removing and servicing the guns 7R and 7L. The ball turret 6 is suitably mounted upon its vertical axis A—B by means of the top bearing support 9 attached to the cross member 5e and by the bottom bearing support member 10 suitably supported from the fuselage formers 5f and the associated fuselage structure. These bearing supports 9 and 10 receive the upper and lower vertical stub shafts 23 attached to the arcuate ring 6f of the turret wall and about which vertical axis A—B the turret may pivot in azimuth. To drive the turret in azimuth as described above by the motor 6b and the gearing 6c, there is provided a driving member or gear sector 11 having an upwardly offset central or hub portion 11a suitably attached to the upper portion of the arcuate ring 6f of turret 6. To this gear sector 11 may preferably be attached the mechanism by which the ammunition chutes 8R and 8L are automatically guided. The ring 6f therefore rotates with the turret in azimuth only and the remainder of the turret proper rotates in elevation with respect to the ring 6f.

The improved chute guide actuating mechanism is shown to an enlarged scale in the plan view in Fig. 4 wherein the azimuth drive gear sector is indicated by the numeral 11 and its upwardly offset hub portion shown at 11a, having the turret upper stub shaft 23 passing through its bore at the central vertical axis A—B. On each side of the central axis E—F of the sector 11 there is pivotally mounted the short rearwardly extending levers 12 and 13 which are suspended from the sector 11 by the pivots 14 and 15. At their rearward

terminals the short levers 12 and 13 are pivotally connected to the secondary levers or links 16 and 17 by means of the pivot bolts 18 and 19, respectively. The links 16 and 17 extend toward each other and overlap at the longitudinal centerline E—F of the turret at which they are interconnected by the pivot bolt 24, the sector 11 being suitably recessed at its underside at 11b to provide clearance for the head of the pivot bolt 24. The latter also serves to join the adjacent ends of the links 16 and 17 to the arcuate guide track 22, the upper and lower terminals of which are bored to receive the stub shafts 23 about which they are free to pivot in azimuth about the vertical axis A—B, both with respect to the aircraft and the turret. The track 22 is preferably T-shaped in cross-section, as more particularly shown in Fig. 5, with the stem of the T-portion removed adjacent its terminals to provide flattened portions having greater clearance. The track 22 is pivotally mounted for limited movement in azimuth with respect to the aircraft and with respect to the turret 6 and is automatically positioned about the circumference of the forward portion of the turret, being disposed normally in the vertical longitudinal plane defined by the axes A—B and E—F. The levers 12 and 13 are arranged to abut or engage the fixed posts or stops 20 and 21, respectively, attached to the fixed fuselage structure, the levers 12 and 13 engaging the stops 20 and 21 as the turret swings in azimuth to the right or to the left, as indicated by the broken lines R and L, in Fig. 4. The track 22 accordingly serves as a cam or guide member and is automatically pivoted within a limited angle about its axis A—B as the turret 6 is moved in azimuth.

At the forward central position of the turret 6, there is provided a guide roller assembly 25, which is shown in Figs. 2 and 3 and in greater detail in Fig. 5. This assembly 25 is comprised of a cross-tie frame 26 to which are attached the pivot bolts 27 and 28 upon which the flanged guide rollers 29 and 30 are free to rotate, as well as the smaller diameter rollers 31 and 32 which engage the lateral edges of the abovementioned T-section track 22. The pivot bolts 27 and 28 also support the brackets 26a and 26b, between which are also pivotally mounted the control rods 33 and 34 by means of the pivot bolts 35 and 36. A secondary guide means consisting of a pair of vertically spaced horizontal guide tracks 37 and 38 are supported from the adjacent faces of the turret 6 (and not the ring 6f) by means of the attachments 38a. It is between these vertically spaced horizontal tracks 37 and 38 that the flanged guide rollers 29 and 30 are disposed and engaged such that the guide roller assembly 25 is adapted to be moved laterally as the track 22 is rocked about the vertical axis A—B.

Each of the flexible ammunition chutes 8L and 8R enters the turret 6 through an ammunition chute guide consisting of an adapter fairlead or guide such as 39 and 40 which are rotatably journaled within the frames 41 and 42 secured to the turret structure. The roller assembly 25 is connected by the short control rods 33 and 34 to the adapters 39 and 40, respectively, by the pivotal connections 33a and 34a. The opposite terminals of each of these control rods are connected to the pivots 35 and 36, being of the universal joint type in order that the control rods may follow the paths defined by the rotation of the adapters 39 and 40, as well as that within which the guide roller assembly 25 is confined by movement along the length of the track 22 as the turret is rotated in elevation and laterally with the track 22 and with respect to the turret as the latter is rotated in azimuth.

The operation of the improved ammunition feed chute guide mechanism is as follows: Movement of the turret 6 such that the guns 7 are trained toward the left, in azimuth, from the central position shown in Figs. 2 and 4, toward the position of Fig. 3, will result in engagement of the right hand lever 13 (as it moves in

the counterclockwise direction) with the fixed stop 21 as shown in Fig. 4. This moves the lever 13, as well as the pivotally interconnected members 12 and 22, in the same direction, namely, toward the left of its central position with respect to the turret 6, and the axis E—F, or toward the lines indicated at L in this figure. Inasmuch as the gear sector 11 and the turret 6 upon which it is mounted, are both moving in the counterclockwise direction in Fig. 4 about the vertical axis A—B, the pivot 14 is moving away from the fixed stop 20 and this permits sufficient clearance for the clockwise rotation of the short lever 12 about its pivot 14. As the turret continues to be traversed in azimuth to the left, the short lever 13 is being cammed against the fixed stop 21, which serves as a detent, imparts pivotal movement to the track 22 in the same direction, namely, counterclockwise or lagging with respect to the movement of the turret, such that the track 22 is moved to the left of its normal position central with the ring 6f at the fore and aft axis E—F to that indicated in the perspective view in Fig. 3. The track 22 becomes in effect a circumferential or arcuate guide track and serves to carry the roller assembly 25 with it to the left as also shown in Fig. 3.

The fixed tracks 37 and 38 attached to the turret serve to confine the rollers 29 and 30 of the assembly 25 to an arcuate path about the front spherical face of the turret while maintaining the same in a horizontal plane. As the track 22 approaches the adapter 39 for the left ammunition chute 8L, the latter is compelled to rotate in the counterclockwise direction within its guide frame 41 along its rollers 39c, as shown in Fig. 6. At the same time the leading adapter 40 is moved a further distance forward than the track 22, with the result that the adapter 40 is rotated within its frame in the counterclockwise direction in such manner that the chute guide slot 40b within the adapter 40 is rotated from its upwardly and outwardly inclined neutral position of Fig. 2 to the substantially vertical position as shown in Fig. 3. As a result the relatively flattened outer face of the flexible ammunition chute is guided in close proximity to the edge of the opening 5d in the fuselage, being that position and attitude of the ammunition chute which permits the closest approach of the center of the circular adapter to the edge of the opening at its closest point of approach.

If in addition to the fully traversed position of the turret shown in Fig. 3, as the guns 7 are rotated in azimuth to their extreme position to the left, should the guns then also be directed upwardly requiring rotation of the turret about the horizontal axis for elevation of the guns, and downward movement of the forward surface of the turret, the track 22 (as well as the ring 6f) are maintained in the position shown in Fig. 3 with respect to the movable portions of the turret. The downward movement of the horizontal guide tracks 37 and 38, and the extent to which the track 22 has been offset, or has lagged from its normal central position, imparts clockwise rotation to each of the chute adapters 39 and 40 such that the approaching chute 8R continues to remain substantially parallel to the adjacent wall surface at the opening and at its point of minimum clearance, and assumes an attitude more nearly that shown in Fig. 2. It will, of course, be understood that where the turret is rotated in azimuth in the opposite direction the left chute 8L is rotated or twisted into a substantially vertical position when the turret is simply rotated in azimuth, and to inclined, but substantially parallel, positions when the movement of the turret results in combined azimuthal and elevational movements. Inasmuch as the adapters 39 and 40 are normally positioned in the lower hemisphere of the spherical turret 6, downward and rearward training of the guns, or depression of the turret in the elevational sense, brings the chute adapters nearer the mean horizontal plane of the turret or to similar posi-

tions in the upper half of the turret at which the clearances are not as small or as critical as those which prevail in the lower half of the turret upon opposite movement of the turret when the guns are elevated upwardly. It will also be apparent that the mechanism is such that the adapters are not moved when the turret is rotated in elevation only, without azimuthal movement.

It will, accordingly be noted that an appreciable increase in the range of movement of the turret is permitted by the coordinated guidance of the flexible ammunition chute by positive movement of their adapter guides by the actuating and guiding mechanism which has been disclosed. By means of the improved guide mechanism, an experimental turret installation of the Emerson ball type having a cone of fire of but 50 to 60° was increased to approximately 90°. The improved construction is also applicable to nose and other installations and is not limited to the tail type arrangement shown and described.

Other forms and modifications of the present invention, both with respect to its general arrangement and the details of its several parts, will become apparent to those skilled in the art after reading the foregoing description, but all are intended to come within the scope and spirit of this invention, as more particularly set forth in the appended claims.

I claim:

1. In a gun turret installation, an aircraft body, a turret having a pivotal mounting relative to said body positioned for rotation within an opening in said body, a drive member fixed to said turret, an arcuate track member coaxially mounted upon said turret pivotal mounting for rotation therewith and with respect thereto, an ammunition feed chute extending from within said body through a wall of said turret to the interior thereof, pivotal means operatively connecting said drive member with said arcuate track member engageable with said body for imparting relative pivotal movement to said track member through a lesser angle in the same direction as said driven movement of said turret secondary guide means carried by said turret disposed normal to said track member for reception of a roller means, roller means for engaging both said track member and said secondary guide means, and ammunition chute guide means movably mounted upon said turret for positioning by said roller means in accordance with the relative movement of said track member with respect to said turret for coordinated guidance of the ammunition feed chute in accordance with the pivotal movement of said gun turret to provide greater clearance as said feed chute is rotated with said turret toward said body opening.

2. In a gun turret installation, an aircraft body, a turret having a pivotal mounting relative to said body positioned for rotation in azimuth and elevation, a drive member fixed to said turret, power means engaging said drive member for driving said turret in azimuth, an arcuate track member coaxially mounted upon said turret pivotal mounting for azimuthal rotation therewith and with respect thereto, abutment means carried by said body for limiting movement of a pivotal member, pivotal link means operatively connecting said drive member with said arcuate track member engageable with said abutment means for imparting relative azimuthal movement to said track member in a lagging direction with respect to the driven azimuthal movement of said turret, and ammunition chute guide means movably mounted upon said turret and operatively connected to said track member for positioning said ammunition chute guide means in accordance with the relative movement of said track member for coordinated guidance of the ammunition feed chute in accordance with the azimuthal movement of said gun turret.

3. In an aircraft gun turret installation, an aircraft body, a turret having a pivotal mounting relative to said body positioned for rotation in azimuth and elevation, a drive member fixed to said turret, power means engaging

said drive member for driving said turret in azimuth about a normally vertical axis, an arcuate track member coaxially mounted upon said turret pivotal mounting for azimuthal rotation therewith and with respect thereto about said vertical axis, abutment means carried by said body for limiting movement of a pivotal member, pivotal link means operatively connecting said drive member with said arcuate track member engageable with said abutment means for imparting relative azimuthal movement to said track member in a lagging direction with respect to the driven azimuthal movement of said turret, and ammunition chute guide means including a roller assembly engaging said track member movably mounted upon said turret for positioning in accordance with the relative movement of said track member for coordinated guidance of the ammunition feed chute in accordance with the azimuthal movement of said gun turret irrespective of the elevational movements thereof.

4. In a gun turret installation for an aircraft including a ball turret having a pivotal mounting relative to the aircraft, a gun carried by said turret, a flexible ammunition chute extending from within the aircraft through a wall of said ball turret to said gun and drive means for rotating said turret and said gun about one of the rotational axes of said turret, the improvement of a guide element rotatably mounted within the wall of said ball turret for guiding said chute therethrough and a camming means operatively connected to said guide element and pivotally mounted upon said turret for rotation therewith and with respect thereto, said camming means operatively connecting the aircraft with said guide element whereby the relative position of said ammunition chute with respect to the wall of said turret is changed by said guide element and said camming means in a predetermined manner in accordance with the positions through which said drive means rotates said turret.

5. In turret construction, a vehicle body, a turret having a pivotal mounting relative to said body and positioned within an opening in said body, an adapter element movably carried by and forming a portion of the wall of said turret, an ammunition chute extending through said adapter element for feeding ammunition from a source of ammunition within said body to the interior of said turret, and guide means operatively associated with said turret and with said body for imparting predetermined movements to said adapter element and said ammunition chute that are coordinated with the movement of the turret whereby the adapter element and ammunition chute have a predetermined position corresponding to any particular position of said turret with respect to said body.

6. In gun turret construction, an aircraft body, a turret having a rotatable mounting relative to said body positioned within an opening in said aircraft body, means for rotating said turret about at least one axis, a flexible ammunition chute movably carried upon said turret in a region spaced from said axis for feeding ammunition from the interior of said body through a wall of said turret to the interior of said turret, and guide means operatively contacting said ammunition chute including a pivotal linkage operatively connected with said gun turret rotating means and engageable with said aircraft body for imparting coordinated guiding movements to said ammunition chute movably carried by said turret both with respect to said turret and with respect to said aircraft body for facilitating a maximum range of movement of said turret with respect to the opening in said aircraft body.

7. In a gun turret installation, an aircraft body, a turret having a pivotal mounting relative to said body positioned for rotation within an opening in said body, a drive member fixed to said turret, an arcuate track member coaxially mounted upon said turret pivotal mounting for rotation therewith and with respect thereto, an ammunition feed chute extending from within said body

through a wall of said turret to the interior thereof, pivotal means operatively connecting said drive member with said track member engageable with said body for imparting relative pivotal movement to said track member in the same direction but through a lesser angle than said driven movement of said turret, and ammunition chute guide means movably mounted upon said turret operatively connected to said track member whereby said ammunition chute guide means is predeterminately positioned with respect to said turret in accordance with the relative movement of said track member with respect to said turret for coordinated guidance of the ammunition feed chute in accordance with the pivotal movement of said turret to provide greater clearance as said feed chute is rotated with said turret toward said body opening.

8. In an aircraft, an ammunition feed mechanism for a gun fixed to a turret movable with respect to the aircraft about an axis fixed with respect to the aircraft, power means for moving said turret about said axis, an apertured adapter element rotatably mounted upon said turret at a point remote from said axis, a wall of said aircraft defining an opening about said turret, a flexible ammunition chute extending from a point outside said turret through the aperture in said adapter element to said gun at a point within said turret and camming means op-

eratively connected to said adapter element engageable with the aircraft upon movement of said turret and said adapter element toward a wall of said aircraft for rotating said adapter element and the adjacent portion of said ammunition chute in a direction parallel to said adjacent wall upon movement of said turret to thereby facilitate the feed of the ammunition through said flexible chute to said gun and provide greater clearance with respect to said adjacent wall.

5 10 15 20 25 9. An ammunition feed mechanism of the type called for by claim 8 characterized by said camming means including an arcuate element pivotally mounted on the aircraft for rotation about said axis operatively connected to said turret for rotation through a lesser angle than that through which said turret is rotated upon movement of said turret.
